UNITED STATES PATENT OFFICE.

HUGO ABELES, OF NEW YORK, N. Y.

DESIGN FOR A DOLL PINCUSHION.

Application filed February 1, 1928. Serial No. 25,122. Term of patent 7 years.

To all whom it may concern:

Be it known that I, HUGO ABELES, a citizen of the United States, residing in New York city, borough of the Bronx, in the county of Bronx and State of New York, have invented a certain new, original, and ornamental Design for Doll Pincushions, of which the following is a specification, reference being had to the accompanying drawings, forming a part thereof, of which—

I claim:

The ornamental design for a doll pin cushion as shown.

HUGO ABELES.
